(57) **CLAIM**

The ornamental design for a light modifier as shown and described.

DESCRIPTION

FIG. 1 is a top perspective view of a light modifier showing one embodiment of our new design;

FIG. 2 is a bottom perspective view thereof;

FIG. 3 is a bottom view thereof;

FIG. 4 is a top view thereof;

FIG. 5 is a first side view thereof;

FIG. 6 is a second side view thereof;

FIG. 7 is a top perspective view of a light modifier showing another embodiment of our new design;

FIG. 8 is a bottom perspective view thereof;

FIG. 9 is a bottom view thereof;

FIG. 10 is a top view thereof;

FIG. 11 is a first side view thereof;

FIG. 12 is a second side view thereof;

FIG. 13 is a top perspective view of a light modifier showing another embodiment of our new design;

FIG. 14 is a bottom perspective view thereof;

FIG. 15 is a bottom view thereof;

FIG. 16 is a top view thereof;

FIG. 17 is a first side view thereof;

FIG. 18 is a second side view thereof;

FIG. 19 is a top perspective view of a light modifier showing another embodiment of our new design;

FIG. 20 is a bottom perspective view thereof;

FIG. 21 is a bottom view thereof;

FIG. 22 is a top view thereof;

(Continued)

FIG. 23 is a first side view thereof; and,
FIG. 24 is a second side view thereof.
The broken lines in the drawings are included to show
portions of the light modifier that form no part of the claimed
design.
